(57) **CLAIM**

The ornamental design for a loudspeaker cabinet, as shown.

DESCRIPTION

FIG. 1 is a bottom elevation view of a loudspeaker cabinet showing my new design in a square-edged form;

FIG. 2 is a front elevation view thereof;

FIG. 3 is a side elevation view thereof;

FIG. 4 is a perspective view showing the side disclosed in FIG. 3, the top, and front thereof;

FIG. 5 is a bottom elevation view of my new design showing an alternative round-edged form;

FIG. 6 is a front elevation view of the round-edged form thereof;

FIG. 7 is a side elevation view of the round-edged form thereof; and,

FIG. 8 is a perspective view of the side disclosed in FIG. 7, the top, and front of the round-edged form thereof.
